UNITED STATES PATENT OFFICE.

BYRON L. GREEN, OF MOUNT CLEMENS, MICHIGAN.

CLASP.

No. 885,993.

Specification of Letters Patent. Patented April 28, 1908.

Application filed November 25, 1907. Serial No. 403,622.

To all whom it may concern:

Be it known that I, BYRON L. GREEN, a citizen of the United States, residing at Mount Clemens, in the county of Macomb, State of Michigan, have invented certain new and useful Improvements in Clasps; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to clasps, and more particularly to those of resilient wire, or spring metal.

The object of the invention is to provide a simple and inexpensive clasp of such construction as to present opposed clamping jaws or members adapted to clamp two articles together, as for instance a drawer leg and stocking, so as to serve as a garment or stocking supporter.

25 A further object is to provide such a clasp of a shape to conform to the contour of the leg to enable it to lie closely thereto and of such a structure as to enable the ready entrance of the articles or garments between the clasping or clamping jaws.

The above objects are attained by the device illustrated in the accompanying drawings, in which:—

35 Figure 1 is a general view, showing the application of my improved clasp for supporting a stocking leg. Fig. 2 is a perspective view of the clasp. Fig. 3 is a plan view thereof. Fig. 4 is an enlarged sectional view as on line 4—4 of Fig. 1. Fig. 5 is a side 40 elevation of the clasp, and Fig. 6 is an enlarged view in elevation, showing the clasp in position for securing the top of a stocking to a drawer leg.

Referring to the characters of reference, 1 45 designates a loop at the end of the clasp which is preferably circular in form and from the terminals of which extend the clasping members or jaws 2 and 3, respectively. These jaws or jaw members lie approximately parallel, the jaw 2 being provided with a short upwardly and outwardly turned end 4, and the jaw 3 with a longer downwardly and outwardly turned end 5. The loop and integral jaw members are formed 50 preferably of spring wire of suitable gage and said jaws and loop are curved laterally,

as clearly shown in Fig. 3 so as to conform to the rounded shape of the leg of the wearer. The large loop 1 at the end of the clasp adds considerably to the resiliency of 60 the jaw members, and at the same time serves as a kind of handle which may be grasped by the thumb and finger when placing the clasp in position for use.

In applying this improved clasp as a 65 stocking supporter, a fold, as at 6, is made in the leg 7 of the drawer, and a portion, as at 8, of the top of the stocking leg 9 is taken up therewith. The folded portion of the drawer leg and the top portion 8 of the stocking leg 70 are entered between the flared ends of the jaw members and said members forced thereon so as to clamp said parts between them, as clearly shown in Figs. 4 and 6. The resiliency of the spring wire of which the 75 clasp is formed, causes the jaw members to clasp or grip said garments with such force as to hold them securely together and retain the clasp in position thereon, said clasp when being employed in this manner presenting its curved face so as to conform to the contour of the leg and lie closely thereto, avoiding any unusual projection and obviating annoyance and inconvenience to the 80 wearer.

85 It will be noted that the construction of the clasp is such as to cause the clamping jaws to stand approximately parallel so that the full gripping surface of the jaws is made available. By causing the outer end of the 90 lower jaw to extend beyond that of the upper jaw, it is made to serve as a guide for entering the goods between the jaws, facilitating the placing of the clasp in position. By making one of the jaws shorter than the 95 other and with less projection at its end, the liability of the ends of the jaws catching upon anything passing over them is materially reduced.

Having thus fully set forth my invention, 100 what I claim as new and desire to secure by Letters Patent, is:—

1. A clasp formed of resilient metal consisting of a relatively large loop at one end, substantially circular in form, jaw members 105 formed integral with and projecting from the terminals of said loop in parallel relation, the inner faces of said jaw members being contiguous and the whole clasp curved laterally from end to end thereof, the terminals of the 110 jaw members being turned outwardly in opposite directions to facilitate the entrance of

articles between said jaws, and one of the
jaw members being longer than the other.

2. A clasp formed of spring metal, con-
sisting of a relatively large loop at one end,
5 integral jaw members projecting from the
terminals of said loop, said jaw members ex-
tending in parallel relation and the whole
clasp comprising the loop and jaw members

being bent laterally to describe the arc of a
circle. 10

In testimony whereof, I sign this specifi-
cation in the presence of two witnesses.

BYRON L. GREEN.
